UNITED SHOE MACHINERY COMPANY, OF PATERSON, NEW JERSEY, A CORPORA-
TION OF NEW JERSEY.

MACHINE FOR ATTACHING WELTS OR RANDS TO STOCK.

1,081,953.

Specification of Letters Patent.

Patented Dec. 23, 1913.

Application filed March 9, 1912. Serial No. 682,680.

To all whom it may concern:

Be it known that we, JOSEPH GOULDBOURN and HARRY HALLAM, subjects of the King of England, residing at Leicester, Leicestershire, England, have invented certain Improvements in Machines for Attaching Welts or Rands to Stock, of which the following description, in connection with the accompanying drawings, is a specification, like reference characters on the drawings indicating like parts in the several figures.

This invention relates to machines for attaching welts, rands and similar strips of material to stock in the manufacture of boots and shoes, and more particularly to machines for this purpose which embody mechanism for slitting the inner margin of the strip to render the strip more flexible whereby it may be conformed more easily to the outline of the edge of the stock during the attachment of the strip to the curved portions of the stock.

An object of the invention is to improve the organization of the machine as a whole, particularly with respect to the means for controlling the starting and stopping of the machine, the presentation of the work to the machine and the operation of the slitting mechanism.

In machines of the type referred to, as heretofore constructed, the raising of the work support, the starting of the machine, and the throwing into operation of the strip slitting mechanism have each been controlled by a separate treadle or hand lever; and one feature of the present invention is a simplified construction of the machine whereby two or more of the said operations may be controlled by a single manually operable part.

In the illustrated preferred embodiment of the invention a single manually operable part controls not only the operation of the strip slitting device but also the clamping of the work and the starting of the machine. The arrangement is preferably such that by means of the said manually operable part the strip slitting device may be thrown into or out of action at the will of the operator after the said part has effected the starting of the machine or has effected first the clamping of the work in, or its movement into, operative position and then the starting of the machine. In the illustrated con-

struction, the manually operable part has 55 a lost motion connection with the starting and stopping means, is arranged to operate a cam of which the function is to raise and lower the work support into and from operative position, and is connected with a reciprocating actuator of which the path of movement can be shifted by the said manually operable part so as to bring the actuator into operative relation to the slitting device when that device is required to be 60 65 operated.

The invention also aims to provide improved slitting mechanism so arranged with respect to the mechanism for inserting the attaching fastenings that by its operation 70 it will facilitate the attachment of the strip to the work and that the coöperation of the two mechanisms will result in an improved quality of work. To this end another feature of the invention is the provision in a 75 machine for securing welts, rands or similar strips of material to stock in the manufacture of boots and shoes of slitting mechanism comprising a knife or cutter arranged to slit the inner edge of the strip by entering the under surface of the strip, that is, the surface which is in contact with the stock when the strip is attached thereto, and moving obliquely through the strip in such direction that in securing the said strip to 80 85 the stock by successive operations of the fastening inserting mechanism each slit portion will, before being secured, override the portion immediately in front of it that has already been attached to the stock.

These and other features of the invention including certain details of construction and combinations of parts will be described in connection with an illustrative machine and pointed out in the appended claims.

Referring now to the accompanying drawings,—Figure 1 is a front elevation of a portion of the head of a machine for inserting fastenings in which the present invention is embodied, part of the table supporting mechanism being shown in section; Fig. 2 is a side elevation, certain parts of the clutch actuating mechanism being shown in section; and Fig. 3 is a perspective of the heel portion of a sole to which a rand has 105 been attached by the machine shown in Figs. 1 and 2.

For convenience of illustration this inven-

tion is shown as embodied in a fastening inserting machine of the kind described and illustrated in United States Letters Patent to L. Goddu, No. 490,625 and to L. A. Casgrain, No. 611,405, to which Letters Patent reference may be had for a more detailed description of parts herein illustrated but not fully described, such description being unnecessary for a complete understanding of the invention of this application.

The nose 1 in which operates a driver 3 carried by a driver bar 5, the oscillating lever 7 carrying the movable cutter of the fastening severing mechanism and held in engagement with a cam on the driving shaft by means of a spring 9, and the feed wheel 11 are illustrated and described in detail in the Letters Patent above referred to. The general operation of the fastening inserting mechanism, described in the said Letters Patent referred to, will not be taken up in detail further than to state that the machine is adapted to cut one by one from a nail strip a plurality of tapered nails and to drive the nails one by one through the welt and into the stock as said stock and welt are fed past the nose 1.

Beneath the nose 1 is a table 13 for supporting the piece of stock A, a guideway 15 being arranged above the table to guide a welt B, preferably tapered at its inner margin as shown in Figs. 1 and 2, into position on the piece of stock thus supported. As will hereinafter appear the table 13 is capable of being rotated and is pressed upward yieldingly by a spring so as to clamp the stock and the welt between itself and the feed wheel 11 whereby the stock and welt will be fed under the fastening inserting mechanism and secured together. Rotation of the table is effected as in the machine of Letters Patent No. 611,405, by means of a long pinion 17 which meshes with the gear 19 integral with the table. During the operation of the machine the stock and welt are held between the work table or support 13 and the feed wheel 11 as has been described, the slitting of the inner margin of the welt is effected when desired by a knife 21, and power is applied to the machine through a clutch of any convenient form such as that shown in the Letters Patent referred to above, said clutch being connected with the actuating rod 23.

In machines of the present type as heretofore constructed the throwing in of the clutch to start the machine, the gripping of the stock and welt between the feed wheel and the work support, and the throwing into operation of the slitting mechanism have each been controlled by a separate means. In order, however, to facilitate control of the several mechanisms referred to, the following construction and arrangement of parts is employed: A treadle 25 is connected by a

rod 27 with a bell crank lever 29 having trunnions 31 mounted in an extension 33 of the machine frame. One arm of the bell crank lever is provided with a cam 37 with which a roll 39 carried in a sleeve 41 is kept in contact by a spring 43 which bears at its lower end against a washer 45 supported on the sleeve 41 and at its upper end against a second washer 47 which abuts the under side of a bearing 49 projecting from the frame 75 of the machine. The sleeve 41 is adapted to slide within a boss on the extension 33 of the frame when actuated by the cam 37, and the washer 45 supports a second spring 51 located within the spring 43. Upon the upper end of the spring 51 rests a washer 53 which in turn supports a tubular extension 55 of the table 13, said extension being loosely mounted in the bearing 49. A rod 57, which at its upper end is threaded into the table or support 13, is slidably mounted in the sleeve 41 and is provided with a head which serves as a stop to limit its upward movement. With this construction the roller 39 is at all times held by the action of the spring in contact with the cam on the arm of the bell crank lever 29; and, when the roller is raised, the stock is held yieldingly against the feed wheel 11, the table being at the same time free to rotate. As will be observed in Fig. 2, the cam 37 is provided with a raised portion for the purpose of raising the work table 13 into yielding contact with the work upon the first step in the depression of the treadle 25, and this raised portion of the cam is concentric with the axis of the trunnions 31 so that the table will remain stationary as regards its height or pressure on the stock upon further depression of the treadle, said further depression being adapted, as will presently be described, first to operate the clutch mechanism for applying power to the machine and thereafter to bring the slitting device into operation.

For the purpose of operating the clutch mechanism the treadle 25 is connected by a rod 59, pivoted to the treadle at 61, with the clutch actuating rod 23; and the rods 59 and 23 are provided with a lost motion connection whereby, before the rod 23 is actuated, the treadle 25 is permitted sufficient downward movement to raise the table 13 in the manner which has been described above. To this end the rod 59 is formed with a 120 socket to receive the lower end of the rod 23, said socket being traversed by a transverse bore 63 of comparatively large diameter through which passes a pin 65; and upon this pin the lower end of the rod 23 125 normally rests, said pin being connected by springs 67 with a cross-piece 69 adjustably clamped upon the rod 23. The rod 23 and its fittings are yieldingly supported by a spring 71 which engages at its upper end an 130

enlargement 73 on said rod and at its lower end a hollow nut 75 threaded into the bushing 77. With this construction, after the treadle 25 has been depressed sufficiently to 5 raise the table 13 so as to grip the stock between said table and the feed wheel 11, the upper wall of the bore 63 will come into contact with the pin 65 so that further downward movement of the treadle will 10 throw in the clutch to start the machine. It will be noted, however, that after the clutch has been thrown in, the spring 67 will permit still further downward movement of the treadle.

15 For the purpose of controlling the actuation of the slitting mechanism by the final step of the depression of the treadle 25 an arm 78 is secured to one of the trunnions 31 of the bell crank lever 29. This arm 78 is 20 bifurcated and carries a transversely mounted, angularly movable pin 82 through which loosely passes a rod 81, said rod being connected at its lower end through the pin 82 and a spring 83 with the arm 78 and at its 25 upper end with one arm 85 of a bell crank lever mounted to turn in bearings in the frame of the machine. The other arm 87 of the bell crank lever last referred to has engagement through a pin 89 with an actuator 30 in the form of a pendulum link 91, said link being provided with a slot 93 to engage the pin 89. This pendulum link 91 is pivoted at 95 to the knife carrier 7 which, in this type of machine, is oscillated to cause the 35 knife to cut fastenings from a nail strip. The pendulum link will thus, during the operation of the machine, be reciprocated continuously; and since connection of the pendulum link with the arm 87 is made 40 through the slot 93 and pin 89, the reciprocation of the link will be permitted without disengagement of said link from the bell crank lever. The slitting knife 21 is reciprocated in a slideway in the frame of the 45 machine by a lever 97 pivoted at its lower end at 99 to the frame of the machine and having its upper end extending through a slot in the knife 21. This lever is normally maintained with the knife in a retracted 50 position by a spring 101 connected with the frame of the machine and with an arm 98 of the lever 97, a screw 103 threaded through said arm engaging a portion of the frame so as to serve as an abutment to regulate the 55 distance to which the knife is retracted. The lever 97 is also provided with another arm 105 having a projection or abutment 107 which is adapted to be engaged at times by a similar projection 109 on the pendulum link 91 during its reciprocation. With this 60 construction the slitting knife 21 will remain stationary as long as the parts are in the positions shown in Fig. 1; when, however, the link 91 is moved angularly a distance 65 sufficient to cause the projection 109 on the

link 91 to engage the projection 107 on the lever 97 the slitting knife will be actuated. Angular movement of the rod 81 to an extent sufficient to cause operation of the knife 21 is arranged to occur during the last portion of the downward movement of the treadle 25, this result being accomplished by using a spring 83 of the proper tension and by properly arranging the various levers as shown.

It has been stated that one of the features of this invention consists in a construction and arrangement whereby the slitting knife or cutter is caused to enter the under surface of the welt and move obliquely through said welt in such a direction that in securing the welt to the stock by the successive operations of the fastening inserting mechanism each tongue will, before being secured, override the adjacent portion of the tongue immediately in front of it. In order to bring about this result, the guideway 15 for the welt B extends in the same general direction as that of the path of the knife but downwardly to meet said path at an acute angle; and in order to insure proper feeding of the welt there may be provided, if required, a guiding device, indicated at 111, which may be of any suitable construction. A heel portion of a sole to which a welt or rand has thus been attached is shown in Fig. 3, the arrow indicating the direction in which the rand was fed. Considering for example the first two tongues 100 and 200 it will be evident that these tongues were formed by the 95 action of the slitting mechanism in the order named. The tongue 100 was therefore secured in place by its respective fastening while the tongue 200 was being crowded forward by the feed mechanism, with the 100 result that the forward portion of the tongue 200 overrode the adjacent portion of the tongue 100. And similarly the forward portion of each succeeding tongue overrode the adjacent portion of the next preceding 110 one.

The operation of the machine as far as concerns the present invention is briefly as follows:—Assuming the machine to be in 115 inoperative position with the table 13 lowered, the workman places the sole or other piece of stock upon the table. Upon depression of the treadle the table is first raised by the cam 37 to clamp the stock and the end of the welt between the table and the feed roll 11. Further depression of the treadle operates the clutch mechanism through the rods 59 and 23 and starts the machine so that the work is fed, fastenings are cut from the strip, and the welt is nailed 120 to the piece of stock. When a curved part of the sole or other piece of stock is reached so that difficulty would be experienced in feeding the welt to the edge a further depression of the treadle renders the slitting 125 130

mechanism operative by shifting the path of the link 91. As soon as the curved part of the stock has been dealt with and the use of the slitting mechanism is no longer required, 5 the treadle is raised sufficiently to remove the path of the projection 109 on the pendulum link 91 from the projection 107 on the lever 97. Thereafter the machine will continue to operate without slitting the welt 10 until upon completion of the welt attaching operation the treadle is raised, whereupon the clutch will first be thrown out and then the table lowered for the removal of the completed work.

15 Throughout the appended claims the word "welt" will be used for convenience but it should be understood that the particular nature and function of the strip which is attached to the piece of stock is immaterial.

Having thus described our invention, what we claim and desire to secure by Letters Patent of the United States is:

1. A machine of the class described having, in combination, means for attaching a welt to stock and means for forming inclined slits in the inner margin of said welt, said last-named means including a cutter and means for forcing said cutter obliquely 25 through said welt from beneath.
2. A machine of the class described having, in combination, means for attaching a welt to stock, a cutter for slitting the inner margin of said welt, means for guiding said welt from above down, over and past the edge of said cutter, and means for forcing said cutter obliquely through said welt from beneath.
3. A machine of the class described having, in combination, fastening inserting 40 mechanism, welt and stock feeding mechanism, a guideway for the welt, a slitting

knife located beneath said guideway, and means for reciprocating said knife in a path extending longitudinally of said guideway 45 but at an angle thereto.

4. A machine of the class described having welt feeding mechanism including separable feeding members in combination with a controlling member movement of which 50 successively causes relative movement of said feeding members and applies power to the machine.

5. A machine of the class described having welt feeding mechanism including separable feeding members and normally inoperative welt slitting mechanism in combination with a controlling member movement of which successively causes relative movement of the feeding members and renders 60 the slitting mechanism operative.

6. A machine of the class described having normally inoperative mechanism for slitting a welt in combination with a controlling member movement of which successively applies power to the machine and renders the slitting mechanism operative.

7. A machine of the class described having welt feeding mechanism including separable welt feeding members and normally inoperative welt slitting mechanism in combination with a controlling member movement of which successively causes relative movement of the feeding members, applies power to the machine and renders the slitting mechanism operative.

In testimony whereof we have signed our names to this specification in the presence of two subscribing witnesses.

JOSEPH GOULDBOURN.
HARRY HALLAM.
